BILL HOLDING AND DISPENSING DEVICE

Harold Lever, Chicago, Ill.

Application February 1, 1947, Serial No. 725,797

10 Claims. (Cl. 129—35)

1
This invention relates to an improved bill-holding and dispensing device of the type dealt with in my prior United States patents, Numbers 1,405,850, 1,781,022, 1,781,023 and 1,821,350, and it has to do more especially with a device of that character which is adapted to be mounted in a receptacle such as the cash drawer of a cash register.

One of the objects of my present invention is to provide an improved arrangement for releasably holding the bills which has the advantage of materially facilitating insertion and withdrawal thereof—thus speeding up the work of making change. To that end a feature of the invention consists in mutually offsetting the bill-confining lugs at either side of the bill-supporting top plate so that they are not positioned directly opposite one another. This new arrangement renders insertion of bills into the holder a much speedier operation, and also facilitates removal of bills therefrom.

Another feature which contributes to realization of the same object consists in the provision of small rubber teats which aid the principal bill-confining lugs in holding the bills in place but do not materially obstruct the free or open area which is needed in order to enable a cashier or other person to make bill insertions and withdrawals with a minimum of hindrance and delay.

Another object of my invention is to provide a bill holder and dispenser which is especially well adapted for use where the compartment in which it is to be mounted is shorter than the lengthwise dimension of the bills to be inserted therein—for which reason it is necessary to bend the bills at one end in order to get them into the compartment. To that end I have provided a bill-supporting top plate which is bent upwardly at one end so as to form a positive support for the upwardly bent bills.

Other objects and advantages of my invention will be pointed out in the following detailed description and appended claims.

In the drawings which accompany this specification:

Fig. 1 is a perspective view of my improved bill-holding and dispensing device;

Fig. 2 is a side elevational view of the device mounted in a cash drawer;

Fig. 3 is a top plan view of the same;

Fig. 4 is a detail view in perspective of a slotted bracket which functions as a pivotal anchoring member for one end of one of the two leaf springs on which the top plate is supported;

Fig. 5 is a transverse sectional view;

2
Fig. 6 is a duplication of Fig. 5, so far as the device per se is concerned, but showing, in addition, how the device may be supported on brackets when it is desired to mount the same in a compartment which otherwise would be too deep; and

Fig. 7 is a sectional view taken on line 7—7 of Figs. 3 and 5.

The device illustrated comprises a sheet metal base plate 10, bent at one end to form an upstanding leg 11 to which is attached an extension screw 11a having an enlarged disc-like head 11b which is adapted to bear against one of the interior wall surfaces of a cash drawer 12—the compartment itself being identified by reference numeral 13.

Mounted on the top surface of base plate 10 is a bar or plunger 14, which is continuously urged by a coil spring 45 (see Fig. 2) in the direction indicated by arrow 15 (Fig. 1) and slidably confined near one end of the base plate by a slotted sheet metal guide member 16, which may be formed up from the base plate. The outer end of the bar or plunger 14 is bent upwardly to form a foot 17 which is adapted to bear against the opposite wall of the compartment 13, as clearly shown in Fig. 2. The lengthwise range of movement of plunger 14 is such that the device may be firmly secured in place thereby in compartments which vary in length to a considerable extent. The spring 45 serves to urge the plunger outwards and has one end thereof connected to an upstanding lug on the base plate 10 and its other end connected to an upstanding lug on the inner end of the plunger. The screw 11a is disposed at one end of the base plate and the foot equipped end of the plunger is located at the other end of the base plate. When the compartment 13 is not of greater length than is usually encountered in cash registers, screw 11a may be omitted in which event leg 11 bears directly against the adjacent compartment wall.

A bill-supporting sheet metal top plate 18 is resiliently supported on a pair of semi-elliptical type leaf springs 19 and 20, each of which is curled at one end to form an eye 21 by means of which the springs are pivotally anchored to angle brackets 22—see Fig. 4—each having a slot 23 through which the end of the spring is passed. Said brackets 22 may be welded or otherwise firmly secured to base plate 10. The end of each spring remote from brackets 22 bears against the base plate top surface and is free to slide thereon so as to allow the springs to flex. Suitable lugs 46, punched out of base plate 10 and bent upwardly,

serve as lateral guides for the free ends of the springs. Top plate 18 is riveted or otherwise suitably secured to springs 19 and 20 and is thus adapted to be depressed by downwardly directed pressure brought to bear thereon from above.

The top plate 18 is preferably convexed upwardly or bent downwardly at an acute angle along its lateral edges, as clearly shown in Figs. 5 and 6, for the purpose of buckling the bills upwardly at the center so that they can be easily grasped one at a time between the cashier's thumb and fingers; and said top plate is provided at one end with a pair of ears 24 and 25 which are inclined upwardly at a suitable acute angle whereby to provide support for bills resting on the top plate when the same are bent upwardly at one end (see Fig. 7) as would necessarily be the case when the device is mounted in a compartment which is not long enough to otherwise accommodate the bills lengthwise. Said ears 24 and 25 need not be bent upwardly when the compartment is long enough to accommodate the full length of the bills.

The top plate 18 is cut away at 26 between ears 24 and 25 to provide finger clearance to facilitate reaching under and withdrawing a pile of bills from the device. Ears 24 and 25 are preferably covered with rubber or like material to prevent the user's fingers coming into contact with the edge of the top plate.

A pair of upright sheet metal side pieces 27 and 28 are located at either side of the base plate and top plate and are secured at their bottom ends to the base plate. Each of said side pieces comprises a pair of vertical members 29 and 30 and a cross member 31 which interconnects the upper ends and is integral with the vertical members 29 and 30. Each of the side pieces 27, 28 is reinforced by a stiff angle iron 32, 32, each having a horizontal leg which is welded or riveted to the base plate, and a vertical leg which is similarly secured to the respectively associated cross member 31.

Attached to each cross member 31 is a lug 33, 34 which overlies the adjacent edge portion of top plate 18 and functions as a bill-confining member. Said lugs 33 and 34 are preferably curved on their upper and lower surfaces, convexedly, in more or less streamline fashion and also curved edgewise, as viewed from above, so that their maximum projections are at the midpoints of their lengths. The top surface curvature of the lugs facilitates insertion of bills into the holder, and the lower surface curvature makes for easy withdrawal.

I have found that by mutually offsetting the lugs 33 and 34—by which I mean that the lugs are so located as to be not directly opposite each other transversely of the top plate—bills can be inserted in the holder with much greater facility than is the case where the lugs are oppositely positioned.

As a further means of holding the stack of bills down on the top plate, without materially obstructing the space overlying the bills so as to interfere with the fingers of the person using the device, I have found it desirable to provide a number of soft rubber teats 35—38 inclusive—there being two such teats secured to each cross member 31. Said teats are placed at either end of their respectively associated lugs 33, 34 and spaced therefrom; and each teat is designed to overlie the edge of the top plate so as to engage and slightly overlie the top bill of the stack and thus aid in holding down the edge of the top bill.

While these rubber teats are not large enough to offer any material resistance to withdrawal of the bills, they serve to prevent the adjacent edges from curling up and have proved to be really desirable adjuncts to the lugs 33, 34.

In Figs. 5, 6 and 7, a stack of bills 39 is shown resting on top plate 18; and the manner in which these are secured edgewise and held down by the lugs 33, 34 and the rubber teats 35—38 is clearly depicted in the cross-sectional views, Figs. 5 and 6.

In some instances the compartment in which the above-described device must be mounted is so deep that if the device were placed on the bottom it would not be conveniently within reach; and I have anticipated such contingencies by providing, as shown in Fig. 6, a pair of sheet metal suspension brackets 40, 40 formed to slip over the tops of the compartment walls 41, as shown—said brackets having horizontal portions 40a forming shelves on which the device rests. The brackets may be made to accommodate various wall thicknesses.

Having described my invention, what I claim as new and wish to secure by Letters Patent is:

1. A bill-holding and dispensing device comprising: a base plate, a top plate adapted to provide support for a stack of bills, spring means resting on said base plate and operative resiliently to support said top plate, a pair of upright side pieces attached to said base plate and located at either side of said top plate and extending thereabove, a pair of bill-confining lugs formed with convexly shaped upper and lower surfaces, said lugs being attached respectively to said side pieces and overlying the respective edge portions of said top plate, said lugs being mutually offset so as to engage the stack of bills edgewise at points which are not opposite one another transversely of the top plate.

2. A bill-holding and dispensing device comprising: a base plate, a top plate adapted to provide support for a stack of bills, spring means resting on said base plate and operative resiliently to support said top plate, a pair of upright side pieces attached to said base plate and located at either side of said top plate and extending thereabove, a pair of bill-confining lugs carried by and attached respectively to said side pieces and overlying the respective edge portions of said top plate, said lugs each having a convex top surface and bottom surface adapted to facilitate insertion and removal of the bills, said lugs being mutually offset so as to engage the stack of bills edgewise at points which are not opposite one another transversely of the top plate.

3. A bill-holding and dispensing device comprising: a base plate, a pair of laterally spaced leaf springs of semi-elliptical type, each pivotally anchored at one end on said base plate, the other end of each of said springs being free to slide on said base plate, a top plate mounted on said springs above said base plate, a pair of upright side pieces attached to said base plate and located at either side of said top plate and extending thereabove, each of said side pieces comprising a pair of spaced vertical members and a cross member interconnecting the upper ends of said vertical members, and a pair of bill-confining lugs each formed with convexly shaped upper and lower surfaces, said lugs being carried by and attached respectively to said cross members and overlying the respective edge portions of said top plate, said lugs being mutually offset so as to engage the stack of bills edgewise at points

which are not opposite one another transversely of the top plate.

4. A bill-holding and dispensing device comprising: a base plate, a pair of laterally spaced leaf springs of semi-elliptical type, each pivotally anchored at one end on said base plate, the other end of each of said springs being free to slide on said base plate, a top plate mounted on said springs above said base plate, a pair of upright side pieces attached to said base plate and located at either side of said top plate and extending thereabove, each of said side pieces comprising a pair of spaced vertical members and a cross member interconnecting the upper ends of said vertical members, a pair of angle brackets, each having a horizontal leg secured to said base plate and a vertical leg attached to one of said side pieces, respectively, said angle brackets providing reinforcement for said side pieces, and a pair of bill-confining lugs each having convex upper and lower surfaces, said lugs being carried by and attached respectively to said cross members and overlying the respective edge portions of said top plate, said lugs being mutually offset so as to engage the stack of bills edgewise at points which are not opposite to one another transversely of the top plate.

5. A bill-holding and dispensing device comprising: a base plate, a pair of laterally spaced leaf springs of semi-elliptical type, each pivotally anchored at one end on said base plate, the other end of each of said springs being free to slide on said base plate, a top plate mounted on said springs above said base plate, a pair of upright side pieces attached to said base plate and located at either side of said top plate and extending thereabove, each of said side pieces comprising a pair of spaced vertical members and a cross member interconnecting the upper ends of said vertical members, a pair of angle brackets, each having a horizontal leg secured to said base plate and a vertical leg attached to one of said cross members, respectively, said angle brackets providing reinforcement for said side pieces, a pair of bill-confining lugs carried by and attached respectively to said cross members and overlying the respective edge portions of said top plate, each of said lugs being formed with convex upper and lower surfaces to facilitate insertion and removal of bills, said lugs being mutually offset so as to engage a stack of bills edgewise at points which are not opposite one another transversely of the top plate, and small sized inwardly extending teats carried by each of said cross members adjacent either end of said lugs and spaced from said lugs, said teats being adapted to overlie and engage the respective edge portions of the stack of bills and thus aid in holding the bills on the top plate.

6. A bill-holding and dispensing device comprising: a base plate, a top plate adapted to provide support for a stack of bills, spring means secured to said base plate and operative resiliently to support said top plate, a pair of upright side pieces attached to said base plate and located at either side of said top plate and extending thereabove, a pair of large sized bill-confining lugs having convex upper and lower surfaces, carried by and attached respectively to said side pieces and overlying the respective edge portions of said top plate, and small sized inwardly extending teats carried by each of said side pieces adjacent either end of said lugs and spaced from said lugs, said teats being adapted to overlie and engage the respective edge portions of the stack

of bills in order to aid in holding the bills on the top plate.

7. A bill-holding and dispensing device comprising: a base plate, a pair of laterally spaced, upwardly arched, leaf springs of semi-elliptical type, each pivotally anchored at one end on said base plate, the other end of each of said springs being free to slide on said base plate, a top plate mounted on, and fixedly secured to, the central portions of said springs above said base plate, a pair of upright side pieces attached to said base plate and located at either side of said top plate and extending thereabove, and a pair of bill-confining lugs carried by and attached respectively to the upper portions of the side pieces and overlying the respective edge portions of said top plate, said lugs being formed with convex upper and lower surfaces to facilitate insertion and removal of bills.

8. A bill-holding and dispensing device comprising: a base plate, a pair of laterally spaced leaf springs of semi-elliptical type, each pivotally anchored at one end on said base plate, the other end of each of said springs being free to slide on said base plate, a top plate mounted on said springs above said base plate, a pair of upright side pieces attached to said base plate and located at either side of said top plate and extending thereabove, each of said side pieces comprising a pair of spaced vertical members and a cross member interconnecting the upper ends of said vertical members, a pair of angle brackets, each having a horizontal leg secured to said base plate and a vertical leg attached to one of said side pieces, respectively, said angle brackets providing reinforcement for said side pieces, and a pair of bill-confining lugs each having upper and lower convex surfaces, carried by, and attached respectively to, said cross members and overlying the respective edge portions of said top plate.

9. A bill-holding and dispensing device comprising: a base plate, an elongated top plate spaced above the base plate and adapted to support a stack of bills, a pair of side by side, upwardly arched, semi-elliptical leaf springs disposed beneath and lengthwise of the top plate, having the central portions thereof connected fixedly to the central portion of the top plate, having certain adjacent ends thereof anchored to the base plate and their other ends in sliding engagement with said base plate and serving resiliently to support said top plate, a pair of upright side pieces attached to said base plate, located at opposite sides of the top plate and extending thereabove, and bill-confining lugs attached to, and extending inwards from, the upper portions of the side pieces and overlying the sides of the top plate, each of said lugs being formed with convex upper and lower surfaces to facilitate insertion and removal of bills from said device.

10. A bill-holding and dispensing device comprising: a base plate, an elongated top plate spaced above the base plate and adapted to support a stack of bills, a pair of side by side, upwardly arched, semi-elliptical leaf springs disposed beneath and lengthwise of the top plate, having the central portions thereof connected fixedly to the central portion of the top plate, having certain adjacent ends thereof anchored to the base plate and their other ends in sliding engagement with said base plate and serving resiliently to support said top plate, means on the base plate for preventing said other ends of the springs from spreading laterally away from

one another, a pair of upright side pieces attached to said base plate, located at opposite sides of the top plate and extending thereabove, and bill-confining lugs attached to, and extending inwards from, the upper portions of the side pieces and overlying the sides of the top plates, said lugs each being formed with convex upper and lower surfaces to facilitate insertion and removal of bills from said device.

10 HAROLD LEVER.
